G. E. COOK.

COMMUTATOR.

APPLICATION FILED JUNE 3, 1920. RENEWED FEB. 25, 1922.

1,426,960.

Patented Aug. 22, 1922.

UNITED STATES PATENT OFFICE.

GEORGE E. COOK, OF BROOKLYN, NEW YORK.

COMMUTATOR.

1,426,960.

Specification of Letters Patent. Patented Aug. 22, 1922.

Application filed June 3, 1920, Serial No. 386,345. Renewed February 25, 1922. Serial No. 529,289.

To all whom it may concern:

Be it known that I, GEORGE E. COOK, a citizen of the United States, and a resident of the city of New York, borough of Brooklyn, in the county of Kings and State of New York, have invented a new and Improved Commutator, of which the following is a full, clear, and exact description, this being in part a division of the application Serial No. 338,023, filed by me on November 14, 1919.

The object of the invention is to provide a new and improved commutator or timer more especially designed for use in the ignition systems of internal combustion engines of the multiple cylinder type and arranged to reduce the chance of missing to a minimum.

Another object is to prevent burning out of the circuit wires in the casing of the commutator.

Another object is to prevent short circuiting and to exclude dust and other extraneous matter liable to affect the proper functioning of the commutator.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is an elevation view of the commutator with the engine cam shaft shown in section;

Figure 2 is a cross section of the same on the line 2-2 of Figure 1 and in position on the crank case of the engine;

Figure 3 is a sectional plan view of a portion of the same on the line 3-3 of Figure 1; and

Figure 4 is an elevation view of the commutator with the cap removed.

In my previous application above referred to, the circuit wires are embedded in the casing and directly connected with rim and end wall contacts. This arrangement has the disadvantage that in case a circuit wire burns out it cannot be replaced by another without breaking up the casing. In my present invention the circuit wires are not embedded in the casing and are easily removed in case one is burned out, and the cas-

ing is made hollow to provide a chamber into which extend the circuit wires, the ends of the latter being connected with separate leads embedded in the casing and connected with the rim and end wall contacts and leading to the chamber for connection with the circuit wires. Access is had to the chamber by a suitable removable cap.

The commutator casing 10 is preferably made of fiber or other insulating material and is provided with a metallic ring 11 mounted to turn on a bearing 12 forming part of the crank case 13 of the internal combustion engine on which the commutator 70 or timer is used. The band 11 is provided with a lug 14 connected by a link 15 with a suitable shifting lever or other means for turning the casing 10 with a view to advance or retard the spark in the usual manner. 75

In the rim 20 of the casing 10 is embedded a series of segmental rim contacts 21 and a series of segmental end wall contacts 22 is embedded in the back wall 23 of the casing 10. By reference to Figure 1 it will be noticed that the contacts 21 and 22 are arranged in pairs, with the contacts in each pair arranged in overlapping relation. The rim contacts 21 are successively engaged by a contact member 25, preferably in the form of a piece of carbon mounted to slide radially in an arm 26 of a revoluble member 27 extending within the casing 10 and secured on the cam shaft 28 of the internal combustion engine. The contact maker 25 is pressed outwardly by a spring 29 arranged in the arm 26, as plainly shown in Figure 2, to insure firm contact of the contact maker 25 with the rim contacts 21. A second contact maker 30, likewise in the form of a piece of carbon, 95 is mounted to slide in a longitudinal bearing 31 forming part of the revoluble member 27, and this contact maker 30 is pressed outward by a spring 32 seated in the bearing 31, as plainly shown in Figure 3. It will be noticed that by the arrangement described, the revoluble member 27 causes the contact makers 25 and 30 to successively move into engagement with the corresponding rim contacts 21 and the end wall contacts 22. 100 105

The rim contacts 21 are connected with the inner ends of leads 40 embedded in the casing 10 and extending at their outer ends into an annular chamber 41 formed in the outer portion of the casing 10. Similar leads 110 42 are connected at their inner ends with the end wall contacts 22 and likewise ex-

2
tend into the chamber 41. It will be noticed that the leads 40 and 42 are embedded in the material of the casing 10 in spaced relation with each other, and such leads are 5 not liable to be burned out or otherwise injured when the commutator is in use. The ends of the leads 40 within the chamber 41 are connected with circuit wires 45, and similar circuit wires 46 connect with the inner ends of the leads 42, and the said circuit wires 45 and 46 extend from the chamber 41 through an outlet 47, formed integrally in a handle extension 48 integral with the body. The circuit wires 45 and 46 are insulated in 10 the usual manner and extend through a flexible tubing 50 attached to the outer end of the handle extension 48. An insulated ground wire 55 extends through the flexible tube 50 and through a side opening 56 15 formed in the handle extension 48 to connect with the cam shaft 28 in a suitable manner. It is understood that the circuit wires 45 and 46 are connected with the internal combustion engine in a manner more fully set forth 20 in the application above referred to so that further description of the same is not deemed necessary.

The chamber 41 is normally closed by a suitable cap 60, preferably of the same material as the casing 10 is made, and this cap is provided with a screw 61 threaded into a nut 62 embedded centrally in the wall of the annular chamber 41. By the arrangement described the cap 60 can be readily removed whenever it is desired to gain access to the annular chamber 41 and the parts therein for repairs or other purposes. A spring 70 bears against the cap 60 to hold the ring 11 of the casing 10 in engagement 35 with its bearing 12.

It will be noticed that by having two sets of contacts and contact makers in the casing 10 the chances for missing ignition in any one of the cylinders of the engine are reduced to a minimum especially when both sets of contacts 21 and 22 are used simultaneously. It will further be noticed that in case the circuit between the set of rim contacts 21 becomes defective for any cause 45 whatever then the other set of end wall contacts may be used or vice versa, or, as above

stated, both sets can be used simultaneously. It will further be noticed that by using the embedded leads 40 and 42 and providing the annular chamber 41 for the reception of the circuit wires 45 and 46 proper connection can be made between the circuit wires and the leads and the parts can be inspected at any time by the user removing the cap 60. 55

Having thus described my invention, I claim as new and desire to secure by Letters Patent:—

1. A commutator for the ignition system of a multi-cylinder internal combustion engine, comprising a casing of insulated material and having a rim and an end wall adjacent the rim, a set of rim contacts embedded in the said casing rim, a set of end wall contacts embedded in the said casing end wall, leads embedded in spaced relation 65 in the said casing and connected at their inner ends with the said contacts, conductors connected with the outer ends of the said leads, and a revoluble member mounted to turn and provided with two contact members, of which one is adapted to engage the 70 said rim contacts and the other the said end wall contacts.

2. A commutator for the ignition system of a multi-cylinder internal combustion engine, comprising a casing provided with a rim, a chamber having an integral outlet and a cap for closing the chamber, a set of rim contacts mounted in the rim of the casing, a set of end wall contacts mounted in 80 the end wall of the casing and arranged in overlapping relation with the said rim contacts, leads embedded in the said casing and connected with the said rim and end wall contacts, the said leads extending into the 85 said chamber, a revoluble member mounted to turn in the said casing and provided with two contact members, of which one engages successively the said rim contacts and the other engages successively the said end wall contacts, and conductors extending through the said casing outlet and into the said casing chamber, the inner ends of the conductors being attached to the ends of the said leads within the said chamber. 90

GEORGE E. COOK.
